UNITED STATES PATENT OFFICE.

WILLIAM ROBINSON, OF BOSTON, MASSACHUSETTS.

CAR-TRUCK.

SPECIFICATION forming part of Letters Patent No. 243,798, dated July 5, 1881.

Application filed April 7, 1881. (No model.)

To all whom it may concern:

Be it known that I, WILLIAM ROBINSON, of Boston, in the county of Suffolk and State of Massachusetts, have invented new and useful 5 Improvements in Radial Car-Trucks, of which the following is a specification.

In the accompanying drawings, in which similar letters of reference indicate like parts, Figure 1 is a side elevation of a truck, consisting of a main and two supplemental trucks and a portion of a car-body, embodying my improvements. A portion of one of the axle-boxes is represented as having been removed, the better to illustrate certain details. Fig. 2 10 is a plan view with the car-body removed. Fig. 3 is a vertical section on line $\alpha\alpha$, Fig. 1. Fig. 4 is a similar section on line yy , Fig. 1. Fig. 5 represents an elevation of one of the saddles H and a section of the box upon which 15 it rests, and also a plan view of the under side of said box and saddle. Fig. 6 is a central longitudinal vertical section of the truck and car-body embodying the invention. Fig. 7 is a plan of the under side of that portion of the 20 car-body engaging the eccentric-pin, (below described.) Fig. 8 is a side elevation, showing certain improvements not exhibited in the former figures, and a modification. A sectional view of the equalizing-bar, showing the shape 25 of the guiding-bar M , is also shown in connection with this figure. Fig. 9 is a plan view of the under side of the truck constructed as 30 illustrated in Fig. 8, a portion being represented as broken out and a portion in horizontal section.

A represents the car-bottom; B, the main truck, centrally pivoted at A' to the car-bottom; and C, the supplemental trucks, centrally pivoted at B' to the main truck, and connected by 35 the crossed links C' , each pivoted at both ends to the supplemental trucks C, or equivalent mechanical device.

Extending upward from and rigidly secured to one of the supplemental trucks is the eccentric-pin D. This pin extends up through the transversely long slot B'' in the main truck into the longitudinally long slot E' in the rocking socket E. (See Figs. 2, 6, and 7.) This socket has its bearings E'' longitudinally in 40 the car-bottom. (See Fig. 7.) The object of providing a rocking slotted socket for the admission of the pin D is to prevent undue strain

upon said pin, especially when a swinging bolster is used, as is the case ordinarily in passenger-coaches. A modification might consist 55 of an eccentric-pin rigidly secured to the car-bottom, having its lower end inserted in a slotted rocking socket applied to a supplemental truck—an exact reversal of the device shown.

In practice, when the wheels strike a curve, 60 the rails impart an end movement to the axles F, causing the main truck B to turn on its axis. This movement, by means of the pin D, which is placed eccentrically to or one side of the swiveling-point A' of the car-body, and by 65 means of the centrally-pivoted supplemental trucks C, provided with the connecting-link C' , turns the supplemental trucks so that the axles of all the supplemental trucks are on lines which are radii of the same circle—viz., a circle 70 an arc of which is described by the curved track. The two slots B'' and E' allow the free relative movement of the pin D, and the rocking socket E prevents undue strain thereon, as above described. 75

G G are the equalizing-bars. These differ from the equalizing-bars now in use, which are rigidly secured to the axle-boxes upon which they rest, in that they are adjustable, the main object being to adapt an equalizing-bar to radial supplemental trucks without injuring the efficiency of either. The bars G are suspended 80 from the axle-boxes F' by means of the diagonal hangers or stirrups H' , which are pivoted to the saddles H , resting upon the axle-boxes 85 F'. The shape of the stirrups is shown in Figs. 1 and 4, and of the saddles in Figs. 1 and 5. Guides H'' , preferably made convex, as shown in Fig. 5, upon their inner sides, in order to allow the boxes to turn slightly in the saddles 90 without binding, are provided for controlling the relative movement of the saddles and boxes. The saddles are preferably not secured to the boxes, otherwise than as above described, in order to allow of a slight sidewise movement. 95

I I are springs placed between the equalizing-bar and the main trucks, and having their ends placed in the seats G'' and B''' on said bar and truck. As the car moves around a curve the outer boxes—i. e., those nearer the 100 outer curved rail—move apart, thus through the hangers H' lifting the equalizing-bar G on that side, and hence through the springs I raising that side of the main truck and of the

car-body. At the same time the opposite equalizing-bar is lowered by the inner boxes moving toward each other, thus bringing the inner hangers, H' , to a more nearly vertical position and lowering the side of the main truck and of the car-body near the inner curved rail. Thus it will be seen that in rounding a curve the outer side of the car is raised and the inner side lowered, even when the rails 5 are of the same height, and the greater the curve the greater is this tipping movement.

J are safety-straps extending from the main truck around the equalizing-bar, serving to stiffen it and prevent its vibration, and, in 15 case of the breaking of one or more of the stirrups H' , temporarily supporting it. The loops J' , inclosing the bar, are sufficiently long to accommodate the vertical play of the bar therein.

The bar M, (see Fig. 8,) secured to the main 20 truck independently of the spring and spring-seats, and lying between guides M' on the equalizing-bar G, is for preventing longitudinal movement in said equalizing-bar.

If desired, guides J'' (see Figs. 1 and 9) may 25 be applied to the equalizing-bar next the safety-straps J, thus utilizing them as guiding-bars also.

In many cases the springs I will bear at their upper ends against the main truck B, as 30 shown in Fig. 1, the seat B''' alone intervening; but in some instances the supplemental trucks are of such a shape that the springs are in the way of their inner corners, as in Fig. 9. To accommodate supplemental trucks of this 35 description, a seat is provided for the upper end of each spring below the supplemental trucks C, and yet rigidly secured to the main truck. This seat may consist of a bar, K, as shown in Figs. 8 and 9, extending across the main truck, 40 having its ends bent up and secured thereto, and having its horizontal portion below the supplemental truck, thus allowing it free play; or it may consist of a short bar extending partly across the supplemental truck or other 45 mechanical equivalent or modification of the seat K shown, provided, always, that such seat is rigidly secured to the main truck and extends below the supplemental trucks without interfering with them, to form a seat for 50 the upper end of the spring I.

It will be noticed that the equalizing-bars G are below the axles, thus supporting the weight of the car-body below the axles, keeping the center of gravity low, and hence 55 diminishing the rocking or jarring motion, increasing the steadiness of the car, and adding to the comfort of passengers. It will be understood that the car-body A rests on the main truck B. The main truck rests, through 60 the springs I, on the equalizing-bars G. The equalizing-bars, through the hangers and saddles, are supported by the boxes, and the supplemental trucks, which bear no weight, are allowed free movement with scarcely any friction, their office being to hold the boxes (and 65 hence the axles) in position and to guide the

movement of the same, not to bear the weight of the car.

L (see Fig. 2) are safety-straps, having their ends secured to the main truck, or to a rigid connection, L', therewith, and passing down under a portion of the frame of a supplemental truck, thus securing it in case of accident.

In Figs. 8 and 9 a modification is shown, in 75 which the ends of the equalizing-bar are bent up and rest upon the boxes, a curvature being made—corresponding to a circle whose center is the pivotal point of the supplemental truck nearest to it—in the portions G''' of said bar, 80 resting and sliding on the boxes. (See the sectional portion of Fig. 9.)

It will thus be seen that by means of my improvements radial supplemental trucks and equalizing-bars are adapted to be used on the 85 same car without interfering with each other or injuring the efficiency of either.

Having thus fully described my improvement, what I claim, and desire to secure by Letters Patent, is—

1. In a railway-car, the combination, with 90 the car-body, main truck, radial supplemental trucks, and eccentric-pin D, of a rocking socket adapted to engage eccentric-pin, for the purpose of providing for the necessary relative movement of the pin without danger of 95 injury thereto during the radiation of the trucks, substantially as set forth.

2. In a radial car-truck consisting of the main truck B and supplemental trucks C, the 100 combination of the following elements, viz: an adjustable equalizing-bar suspended below the axles, box-pedestals secured to the supplemental trucks and embracing the boxes in the usual manner, and the independent saddles 105 H, sustaining the equalizing-bar by means of the stirrups H' , substantially as and for the purpose described.

3. The combination of the stirrups H' , constructed as shown, to embrace the equalizing-bar G, with said bar and the axle-boxes F', provided with means for sustaining said stirrups, substantially as and for the purpose set forth.

4. In combination with the axle-boxes F', hangers or stirrups H' , and equalizing-bar G, 115 the saddles H, adapted, substantially as shown, to allow lateral and rotary movement upon the boxes, but to prevent longitudinal movement thereon, for the purpose specified.

5. In combination with the main truck B 120 and equalizing-bar G, the safety-straps J, constructed substantially as set forth.

6. In combination with the main truck B and equalizing-bar G, the guiding-bar M, said bar being independent of the spring-seat and 125 adapted to prevent longitudinal movement in the equalizing-bar, substantially as described.

7. The combination, with the main truck B, supplemental trucks C, equalizing-bar G, and springs I, of the spring-seats K, or their mechanical equivalents, said seats being constructed and adapted to receive the upper ends 130

of the springs below the frames of the supplemental trucks without interfering with their movement, thus allowing said frames to freely radiate between the spring-seats and the main truck, substantially as specified.

8. The combination, with the main truck B and a supplemental truck, C, of one or more

safety-straps, L, secured to one truck and extending around a portion of the other truck, substantially as and for the purpose set forth. 10
